Des. 203,822
Patented Feb. 22, 1966

203,822

HEATSINK

William Venema, North Haledon, N.J., assignor to Vema-line Products Company, Inc., Franklin Lakes, N.J., a corporation of New Jersey

Filed Apr. 20, 1965, Ser. No. 84,879

Term of patent 14 years

(Cl. D26—1)

FIG. 1

FIG. 2

FIG. 3

FIG. 1 is a front elevational view of a heatsink, showing my new design;

FIG. 2 is a side elevational view thereof, both sides being alike; and

FIG. 3 is a bottom plan view thereof, the top having the same appearance.

I claim:

The ornamental design for a heatsink, substantially as shown and described.
